UNITED STATES PATENT OFFICE.

EDWARD G. LUTZ, OF AVALON, PENNSYLVANIA, ASSIGNOR OF ONE-HALF
TO ALBERT A. LUTZ AND WILLIAM J. LUTZ, OF ALLEGHENY, PENNSYLVANIA.

METAL SHOE-SOLE.

SPECIFICATION forming part of Letters Patent No. 729,371, dated May 26, 1903.

Application filed January 31, 1903. Serial No. 141,282. (No model.)

To all whom it may concern:

Be it known that I, EDWARD G. LUTZ, a citizen of the United States of America, residing at Avalon, in the county of Allegheny and State 5 of Pennsylvania, have invented certain new and useful Improvements in Metal Shoe-Soles, of which the following is a specification, reference being had therein to the accompanying drawings.

10 This invention relates to certain new and useful improvements in metal soles for shoes, and relates more particularly to that class of shoes which are used in mill work and the like.

15 The object of the invention is to provide a metal sole which may be applied to any shoe for the purpose of permitting the metal sole to be removed when the same is not required for actual use, thereby permitting the wearing 20 of a lighter and more comfortable shoe.

In describing the invention in detail reference is had to the accompanying drawings, forming a part of this specification, and wherein like numerals of reference indicate 25 like parts throughout the several views, in which—

Figure 1 is a perspective view of the under side of a shoe with my invention applied thereto. Fig. 2 is a central cross-section taken 30 at the hinge of the metal sole. Fig. 3 is a fragmentary side elevation showing means for securing the rear end of said sole to the shoe. Fig. 4 is a side elevation of this device applied to a shoe, a modified form of means for 35 holding the same thereto being illustrated. Fig. 5 is a face view of said means for holding the sole to the shoe.

In the drawings the reference-numeral 1 indicates the forward part of this metallic 40 sole, which is provided with cut-away portions 2 2 for the purpose of decreasing the weight, the strips which are formed between the said cut-away portions having secured thereto or formed integral therewith numerous hobnails or 45 projections 3, which take the place of the hobnails in the ordinary shoe. At the forward ends and sides of this part 1 are formed clamp-pieces 4, which are adapted to engage the sides and top edge of the sole in the 50 manner similar to that which has been used

on skates, &c. The rear end of this part 1 has lugs 5 bent up in a similar manner to the clamp-pieces 4, but for the purpose of forming a pivotal connection between said part 1 and the part 6. At a suitable point forward 55 of the heel there is secured to the sole of the shoe a plate 7, provided with a notched block 8, and at the rear ends of the part 6 there are provided tongue-pieces 9, which are adapted to be inserted under the forward end of the 60 plate 7. The said pieces 1 and 6 will be retained in this position by the connection of the spring 10, which is pivoted in the lugs 11 on the part 6, the rear end of which is in the form of a yoke and which engages the 65 notches in the block 8 on plate 7. This spring is so arranged that it normally engages said notches, and when it is desired to remove this metal sole the spring is withdrawn from the notches by pulling the loop 12 away from the 70 block 8, thereby freeing the metal sole.

It will be noted that by inserting the rear end of the piece 6 under the forward ends of the piece 7, which is secured to the sole of the shoe, piece 6 is held normally in place 75 and there is not opportunity for the same to become disengaged from the shoe.

A modified form of securing the rear end of the piece 6 to the sole of the shoe is shown in Figs. 4 and 5, and it consists in providing 80 the rear end of piece 6' with a yoke or loop 13, which is engaged by the spring-pressed lever 14. This lever 14 is either held in the open or closed position by the action of the release-spring 15 on the flattened portion of 85 the bearing of said lever.

Having fully described my invention, what I claim as new, and desire to secure by Letters Patent, is—

1. A device of the type set forth comprising in combination with a sectional sole means carried on the forward portion of the sole for engagement with the shoe, locking means pivotally mounted on the rear portion of the sole, said rear portion having rearwardly-extending projections, a clamping-plate adapted to receive said extensions, and a rack member carried thereby for engagement with the locking means on the rear portion of the sole, substantially as described. 90 95 100

2. A device of the type set forth comprising in combination with a shoe, a clamping-plate secured thereto, a rack member carried thereby, a pivotally-connected sectional sole, 5 the rear portion thereof adapted to be secured beneath the forward ends of said clamping-plate, and means pivotally secured on said portion adapted to engage with the

10 said rack member to lock the sole thereto, substantially as described.

In testimony whereof I affix my signature in the presence of two witnesses.

EDWARD G. LUTZ.
